To all whom it may concern:

Be it known that I, CHARLES GRAHAM, of Brooklyn, in the county of Kings and State of New York, have invented and produced a new and original Design for a Sink-Leg, of which the following is a specification, reference being had to the accompanying drawings, forming a part thereof.

The leading feature of my design consists in a post and base with a decorated head showing gracefully flowing side parts, straight bars extending up and down near the center and contributory ornaments, all substantially as herein shown.

A is the straight main body.

B is a base extended horizontally, and C are beads extending up and down on the body and flowing into the base.

D is a pendent foliate ornament.

E F is a scroll extending up and down, the end F making a complete elliptical circuit terminating in a foliate ornament G.

H is a central loop of ribbon, and H', H'', are extensions to the left and right respectively.

H², H³, are terminal scrolls, curved upward.

H⁴, H⁵, are side scrolls located under the lateral extensions H', H'', and curved downward.

I, I, are foliate ornaments with graceful swells above.

J, J, are straight parallel uprights rising between and behind the latter, and terminating in scrolls J' at the top.

K, K, are a succession of stepped ornaments of scalloped outline, superposed each partly upon the one below.

What I claim is—

The design for a sink leg herein set forth and described.

In testimony that I claim the invention above set forth I affix my signature in presence of two witnesses.
